(57) **CLAIM**

The ornamental design for a display screen or portion thereof with graphical user interface, as shown and described.

DESCRIPTION

The sole FIGURE is a front view of a display screen or portion thereof with graphical user interface showing the claimed design.

The dot-dash broken lines in the drawings show a display screen or portion thereof and form no part of the claimed design. The remaining broken lines in the drawings, including the evenly lined-through text and the evenly spaced broken lines showing an electronic device and portions of the graphical user interface, form no part of the claimed design.
